VALVE AND PUMP FOR METERING OUT MATERIAL FOR CAPSULATING MACHINES AND THE LIKE

Rex E. Moule, Holden, Mass., assignor to Norton Company, Worcester, Mass., a corporation of Massachusetts

Application December 11, 1948, Serial No. 64,788

10 Claims. (Cl. 103—2)

1

The invention relates to apparatus for metering out liquids which can be thin free-flowing liquids on the one hand or thick viscous liquids on the other hand and the invention also relates to apparatus for metering out solids in a liquid vehicle, and with regard to its more specific features, the invention relates to apparatus for metering out material to fill capsules in a capsulating machine. In one aspect the invention may be embodied in a valve and pump mechanism to deliver simultaneously a plurality of measured quantities of material at spaced positions, and in a specific form these several quantities are equal.

One object of the invention is to provide an improved metering out valve and pump mechanism for a capsulating machine. Another object is to provide valve and pump mechanism of the type indicated which does not leak. Another object is to provide a non-leaking mechanism of the class indicated which will not soon wear out. Another object is to provide a mechanism of the class indicated which operates freely, requiring little power and setting up little or no strain on the machine. Another object is to provide a valve and pump mechanism which will not readily clog and which can be easily cleaned.

Another object of the invention is to provide a precision sliding valve, especially one having a plurality of valve parts, which is very tight when in position to pass the material, but which at other times is free enough to be readily shifted without the use of a great deal of power, thus combining delivery of material without clogging or leaking with a minimum of wear on the sliding element. Another object is to provide a mechanism having one or more of the features indicated which is adjustable to deliver a variable predetermined quantity of material at the several positions. Another object is to provide an apparatus of the type indicated which is rugged and dependable in operation and well adapted for successful use in a capsulating machine which turns out a plurality of capsules for each cycle of operation of the machine. Another object is to provide a mechanism of the class indicated which can have a sliding or moving valve part accurate to only plus or minus many thousandths of an inch in thickness rather than to plus or minus two tenths of a thousandths of an inch, and which nevertheless will be more dependable than a mechanism with the more accurate sliding member due to the mechanical features which are a part of this invention. Another object is to eliminate precision in sliding fit of a valve of the class indicated without loss of ac-

curacy in performance. Another object is to provide a sliding or shifting valve member with mechanism which automatically takes up for wear.

Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings illustrating one of many possible embodiments of the mechanical features of this invention,

Figure 1 is a plan view of a valve and pump mechanism constructed according to the invention.

Figure 2 is a front elevation of the mechanism.

Figure 3 is a side elevation of the mechanism, certain parts being shown in section.

Figure 4 is a fragmentary view on an enlarged scale showing the cam and limit switch for operating the solenoid.

Figure 5 is a vertical sectional view taken on the line 5—5 of Figure 2 and as to a certain part on the line 5—5 of Figure 7.

Figure 6 is a fragmentary sectional view similar to Figure 5 but showing certain parts in a different position and as to one of them being a section along the line 6—6 of Figure 7.

Figure 7 is an elevation on an enlarged scale of a sliding valve member.

Figure 8 is an elevation on an enlarged scale of a pump block.

Figure 9 is an elevation of the rear of the machine showing the driving mechanism for driving the valve and pump mechanism.

The valve and pump of this invention are particularly intended for a capsulating machine of the type disclosed in my copending application Serial No. 48,912, filed September 11, 1948, Patent No. 2,549,327 of April 17, 1951; which is a continuation of my application Serial No. 538,761, filed June 5, 1944, now abandoned. The machine of my copending application makes capsules by

forming a pair of ribbons of gelatine, bringing the ribbons together and forming pockets between them, filling the pockets with material such as vitamins in a liquid vehicle, then by means of dies pressing the two halves of the pockets together thus forming spheroidal capsules and finally disengaging the capsules from the remainder of the joined ribbons. I shall not

illustrate or further describe the machine of my copending application herein since the pump and valve of this invention is a complete mechanism in itself and furthermore the pump and valve of this invention may be applied to capsulating machines operating on entirely different principles from the principles upon which the machine of my copending application operates or the pump and valve of this invention may be applied to other types of machines.

Referring now to Figures 1, 2 and 3, the machine has a wall 20 of any rigid material such as steel which, so far as this invention is concerned, constitutes a frame or support for the mechanism. Secured to the wall 20 in any suitable manner is a steel plate 21. Referring now to Figures 3 and 5, secured to the plate 21 is a pump block 25 and in this block are formed a plurality of parallel bores 26 in which operate a plurality of parallel pistons 27 and it is by the displacement of the pistons 27 in the bores 26 that the material is pumped. The bores 26 are thus pump chambers and it is desirable that they be somewhat larger in diameter than the pistons 27 since the material to be pumped in many cases consists of solids in a liquid vehicle and by providing the clearance sticking of the pistons in the bores is avoided. Furthermore, while for reasons of manufacture the bores 26 will usually be cylindrical they could, so far as the mechanical functioning of the pump is concerned, have many other shapes. For similar reasons the pistons 27 are preferably cylindrical and as illustrated they are unidiameter rods and in order that they shall not contaminate the vitamins they are preferably made of a stainless steel and so is the pump block 25.

The pistons 27 extend through screw threaded stuffing box members 28 and packing such as leather packing 29 and through close fitting bores 30 in the block 25 into the bores 26. The pistons 27 extend into parallel bores 33 in a piston block 34 which has, as shown in Figures 2 and 5, parallel bushings 35 extending through it. The bushings 35 surround parallel rods 36 which extend from brackets 37, secured to the steel plate 21, to the pump block 25, extending into bores therein. The parallel rods 36 are, by the brackets 37 and the pump block 25, held fixedly in position as the piston block 34 slides up and down thereon thus reciprocating, preferably intermittently, the pistons 27 in the bores 26. All of the pistons 27 are rigidly secured to the piston block 34 by means of pins 40 driven into fine bores 41 in the piston block 34 and through the pistons 27 themselves.

Referring now to Figure 9, the machine has a motor 45 upon the shaft 46 of which is a sprocket gear 47 driving by means of a chain 48 a sprocket gear 49 on a shaft 50 of a speed reducing mechanism 51. The output shaft 52 of the speed reducing mechanism 51 has thereon a sprocket gear 53 which drives, by means of a chain 54, a sprocket gear 55 on a shaft 56 upon which is another sprocket gear 57 driving by means of a chain 58 a sprocket gear 59 upon a shaft 60 and also driving a sprocket gear 61 on a shaft 62, and an idler 63 on a shaft 64 is used to take slack out of the chain 58. The motor 45 and the speed reducing mechanism 51 are attached to a horizontal shelf 65 projecting from the wall 20. The various shafts 56, 60, 62 and 64 project to the rear of the wall 20 while the shaft 62 extends through it. The shafts 56 and 60 have functions in the capsulating machine

which are irrelevant to this pump and valve mechanism, but the shaft 62 is shown in Figure 5 and is journaled in a bushing 63 in the wall 20 and the steel plate 21 and has in front of the plate 21 in an integral crank pin 70 extending through a bore in a link 72 which reciprocates the piston block 34.

The crank pin 70 rotates continuously but I desire to reciprocate the pistons intermittently, that is to say to cause the pistons 27 to dwell at the end of each stroke for a material length of time. Furthermore it is desirable that the stroke of the pistons should be adjustable. Referring now to Figures 2 and 5, extending through the link 72 and through an arm 75 is a pin 76. The arm 75 is slotted to receive the link 72 and is likewise slotted at the left hand end, Figure 2, to receive the lower end of a block 77 to which it is pivotally connected by means of a pin 78. The block 77 is secured to the piston block 34. As the crank pin 70 rotates, the link 72 acting through the pin 76 oscillates the arm 75 on the pin 78. Upward movement of the arm 75 from the position shown in Figure 2 does not at first have any effect upon the piston block 34 but ultimately portions such as pads 80 on the arm 75 engage the bottom of the piston block 34 and further upward movement of the arm 75 raises the piston block 34.

The slot at the left hand end of the arm 75 is large enough to accommodate the left hand bushing 35 and near the right hand end of the arm 75 is another slot to accommodate the right hand bushing 35. Secured to the right hand end of the arm 75 is an inverted L-shaped member 81 which, during downward movement of the arm 75, eventually contacts an adjustable screw 82 located in a split boss 83 which projects forwardly from a downwardly inclined extension 84 of the piston block 34. Consequently, after a dwell, the downward movement of the arm 75 causes downward movement of the piston block 34 by engagement of the inverted L-shaped portion 81 with the screw 82. The screw 82 can be adjusted to vary the dwell at each end of the stroke and when adjusted it can be rigidly secured in adjusted position by means of a screw 85 extending through the split in the split boss 83. However, perhaps a more important function achieved by this mechanism is that the stroke of all of the pistons 27 can, by adjustment of the screw 82, be varied in length from zero to the maximum stroke provided by the eccentricity of the crank pin 70. The fragmentary section of Figure 6 shows a piston 27 at the top of its stroke and in this illustrative embodiment of the invention the top position of the pistons is invariable. The section of Figure 5 shows a piston 27 nearly in its lowermost position for the adjustment indicated in Figure 2 but by adjusting the screw 82 this lowermost position can be varied from the top position shown in Figure 6 to a position where all of the pistons 27 are level with the bottom of the bores 26. Thereby the amount of medicament or other filling material being pumped into the capsules can be varied within wide limits. This accurate adjustability is highly desirable in a capsulating machine. In this connection I preferably provide scale marks 87 on the member 81 and a line 88 on a member 89 attached to the piston block 34 so that the operator may know the quantity of medicament being delivered for each capsule.

Referring again to Figure 5, extending from

each bore 26 to the front of the pump block 25 is a bore 90 constituting a passage. Above each bore 90 is another bore 91 extending from the front of the block 25 into a chamber 92 which is connected to all of the bores 91 which constitute passages for filling material to flow from the chamber 92. Secured by screws 93 to the top of the piston block 25 is a cap 94 of the shape indicated in Figures 1 and 5 and this cap is slotted to provide a continuation of the chamber 92, the shape of which will be apparent from a comparison of Figure 5 with Figure 1. The block 25 and cap 94 might be made out of one piece of steel but it is simpler to manufacture them out of two pieces as indicated. Secured to the cap 94 by means of screws 95 is a top plate 96 having a slot 97 of the same area as the chamber 92 and in effect forming a continuation of it and this slot 97 opens to the inside of a tank 98 the bottom opening of which has the same shape as that of the slot 97 and the end and side walls of which are welded to the top plate 96 so that the chamber 92, the slot 97 and the tank 98 form a continuous enclosure opening into the several bores 91 (ten of them in this illustrative embodiment) for holding a quantity of medicament and delivering it to all of the bores 91. A feature of the construction is that the walls of the chamber 92 are at a fairly broad dihedral angle to each other and the chamber 92 has a breadth extending beyond the marginal bores 91 so that the medicament does not have to rest in any narrow passage or passages until it comes to the bores 91 which are quite short and in which a given quantity of the medicament will not remain for more than one or a few strokes of the pistons 27. In handling material of this nature it is important that there should be no narrow passages where the material moves slowly and wherein the solid particles might gather together to form a lump and for the same reason it is important that there should be no spots in which medicament can remain without moving. By providing the broad chamber 92 with tapering walls, I have succeeded in avoiding any clogging or caking of the material.

Referring now to Figures 5, 6 and 7, I provide a movable valve member 100 which has ports 101 and ports 102. In Figure 6 a port 101 is shown connecting the bores 91 and 90 and a piston 27 is shown in its top position about to move down and when it moves down it will draw material from the chamber 92 through the bore 91 and through the port 101 into the bore 90 and into the bore 26, or at least the material will move and progress in these bores and port so that some material will be drawn into the bore 26. At the same time all the other pistons 27 move downwardly and ports 101 connect the other bores 91 with the other bores 90 with the same results. This valve member 100 may be a parallelepipedal block of steel having ports 101 and 102 cut in a face thereof as shown. Figure 5 shows the valve member 100 being shifted to bring the ports 102 in position to connect the bores 90 with passages 103 in the piston block 25. In Figure 5 the single piston 27 is shown nearly at its lowermost position for that particular adjustment and about to move upwardly and when it does move upwardly it drives material out of its bore 26 and drives material ahead of it out of the bore 90 and through the port 102 into the passage 103 and into a pipe 104 in a header block 105. At the same time all the other

pistons 27 act likewise, there being in this illustrative embodiment ten pistons 27, ten bores 26, ten bores 90, ten ports 102, ten passages 103 and ten pipes 104, and at a single upward stroke of the piston block 34 medicament is pumped into every one of the ten pipes 104 and the same amount is pumped into each. There is a single header block 105 which holds all of the pipes 104 in line with the passages 103 and this is secured as by screws 106 to the lower front corner of the piston block 25 which is cut off at an angle as shown. Comparing Figures 2 and 5, it will be seen that the collection of pipes 104 is twisted so that whereas together they are in a plane perpendicular to the wall 20 at their lower ends, at their upper ends they are in a plane perpendicular to the first mentioned plane. All of these pipes 104 extend into a header block 110 which is clamped to a header block 111 into which extend mandrel pipes 112 which deliver medicament between the ribbons of gelatin and around which mandrel pipes 112 the gelatin ribbons are pressed to form tubular pockets to receive the medicament; thereafter by mechanism described in my copending application capsules are formed out of pockets but this need not further be described herein. As indicated in Figure 5 the headers 110 and 111 attach the mandrels 112 to the pipes 104 so that each mandrel 112 receives all the medicament delivered by a particular pipe 104. As indicated in Figure 3, one of the header blocks for example the header block 111 is attached to the wall 20 to support both of them and thereby the pipes 104 and the mandrels 112.

Referring now to Figure 9, upon the shaft 62 is a sprocket gear 115 driving a chain 116 which drives a sprocket gear 117, an idler sprocket gear 118 being provided to keep the chain 116 taut. The sprocket gear 117 is keyed to a shaft 120. Referring now to Figure 1, the shaft 120 is journalled in a bushing 121 secured to the rear of the wall 20 and the shaft 120 extends through the wall 20 to the front side thereof. On the front of the shaft 120 is a cam 122 having a hub 123. Inside of the hub 123 is a spring detent 124 which can be seated in either of two holes 125. Integral with the cam 122 is a knob 126 extending to the front of the machine in convenient reach of the operator. This knob 126 extends through a slot 127 in the movable valve member 100 which extends a goodly distance to the right of the pump block 25 and associated parts as clearly shown in Figure 1. Secured to the rear of the movable valve member 100 are blocks 130 and 131 by means of screws 132 and 133. The block 130 extends farther to the rear than does the block 131. When the operator pulls the knob 126 to locate the cam 122 in the position shown in Figure 1, it acts upon both of the blocks 130 and 131 and consequently reciprocates the valve member 100, but intermittently with a dwell between each stroke because of the spacing of the blocks 130 and 131 relative to the cam 122 as shown in Figure 1. But when the operator pushes the knob 126 to move the cam 122 rearwardly on the shaft 120, the cam 122 can no longer act upon the block 131 but it can act upon the block 130 and therefore the movable valve member 100 stays to the left or is shifted to the left and thereafter stays to the left without further reciprocation until the knob 126 is again pulled forward. When the movable valve member 100 is to the left the ports 101 connect the bores 90 with the bores 91 as

shown in Figure 6 and then the pistons 27 agitate the material back and forth in these bores and through the ports 101 without pumping it. This agitation keeps the medicament from congealing.

The movable valve member 100 has one face against the pump block 25 as clearly shown in Figures 5 and 6. The cross section of this member 100 as shown in Figures 5 and 6 is a rectangle and the three other faces shown in these figures fit snugly the three faces of a rectangular slot 140 which extends clear across a block 141 attached by nuts 142 on threaded studs 143 to the pump block 25, the studs 143 extending from threaded holes, not shown, in the pump block 25 through holes, not shown, in the block 141. The foregoing constitutes a support for slidably holding the valve member 100 adjacent the pump block 25.

A particular feature of this invention is the provision of means to force the valve member 100 tightly against the pump block 25 between strokes of the valve member 100, that is to say when it is not moving, but releasing the valve member 100 from pressure during the entire time of every stroke thereof. This feature has several advantages in that, provided the front face of the pump block 25 is ground to a plane fairly accurately and the rear face of the valve member 100 is ground to a plane fairly accurately, an exceedingly tight and close fit is achieved between the pump block 25 and the valve member 100 so that when the valve member 100 is in the position shown in Figure 5 the ports 102 are substantially continuations of the bores 30 and the passages 103 and when the valve member 100 is in the position shown in Figure 6 the ports 101 are substantially continuations of the bores 30 and 31 and there will be no leakage of medicament and nevertheless the thickness of the valve member 100 horizontally does not have to be kept to close tolerances and furthermore wear on the valve member 100 is automatically taken up and yet the valve member 100 requires little force to move it. The mechanism for achieving these results will now be described.

Still referring to Figures 5 and 6, a long rod 150 fits in a rectangular slot 151 extending clear across the block 141 and opening into the rectangular slot 140. The rod 150 fits nicely in the rectangular slot 151 and has a flat 152 extending along its entire length. Referring now to Figures 1 and 2, at the left hand end of the rod 150 is an enlargement 153 and at the right hand end is an enlargement 154. The enlargement 153 extends through a split hole 155 in a lever 156 which is securely clamped to the enlargement 153 by means of a screw 157 extending across the slotted part of the split hole 155. A spring 158 extends from a screw 159 to the lever 156 into which it is hooked through a hole 160 as clearly shown in Figure 3. The screw 159 projects from the end of the plate 21. This spring 158 exerts a light force on the lever 156 to apply a couple to the long rod 150 which by reason of the flat 152 thereon is pressed against the valve member 100. This light clamping force does not prevent easy sliding of the valve member 100 but stops leakage as the ports 101 and 102 move into and out of position and prevents medicament from becoming lodged between the plane faces of the valve member 100 and the pump block 25. When, however, the valve member 100 is at rest, a strong force is exerted upon the lever 156 to exert a strong couple upon the rod 150

to thrust the valve member 100 against the pump block 25 with great force. To that end I provide a solenoid 165 having a coil 166 and a core 167 to which is pivotally attached by a pin 168 a threaded rod 169 having an enlarged portion 170 having a hole for the pin 168. The solenoid 165 is secured to the wall 23 while the rod 169 extends through a hole 173 in a narrow lower end portion 174 of the lever 156. A spring 175 upon the rod 169 extends between a washer 176 against the portion 174 and nuts 177 on the rod 169 so that when the solenoid 165 is energized it can seat (thus avoiding vibration due to the fact it will customarily be energized by alternating current) and when the solenoid seats the spring 175 which is relatively stiff urges the lever 156 in a clockwise direction, Figure 3, to exert by reason of the leverage a very strong force clamping the valve member 100 and the pump block 25 together as above mentioned. I may also provide nuts 178 and a rubber washer 179 on the threaded rod 169 to tighten the spring 175.

Referring to Figures 1 and 4, upon the shaft 120 is keyed a cam 180 which has lobes 181 to engage a roller 182 on the arm 183 of a limit switch 184 secured to the wall 23. Twice during every rotation of the shaft 120 the limit switch 184 is closed and this limit switch 184 is connected in series with the solenoid 165 and a source of power to actuate the solenoid 165 whenever the valve member 100 is at rest. Alternating current power is mentioned because this is the power usually available in shops and factories of all kinds and the machine operates satisfactorily with alternating current of any usual variety such as the 60 cycle current or the 25 cycle current which are usually available in the United States but will operate upon other frequencies. Direct current, if available, would be even better.

In order to secure the pump block 25 to the plate 21 without drilling any more holes from front to back of the pump block 25 I may, as shown in Figures 1 and 3, secure blocks 190 to the pump block 25 by means of screws 191 and secure these blocks 190 to the plate 21 by means of screws 192.

It has been mentioned that the pistons 20 and the pump block 25 are preferably made of stainless steel. Also other parts which are contacted by the medicament should be made of stainless steel or other material which will not contaminate the medicament or at least their surfaces which are contacted by the medicament should have a coating of non-contaminating metal or porcelain or the like. This includes the tank 98 and the movable valve member 100 as well as the pipes 104 and the mandrel pipes 142.

It will be seen that the rod 150 with its long flat 152 is in effect an eccentric shaft and along its whole length acts as a cam for pressing the slide valve 100 against the pump block 25. It will further be seen that when the lever 156 has pressure put thereon by the spring 158 or the solenoid 165 a couple is exerted on the rod 150 exerting pressure against the slide valve 100 all along its length. Other cam or eccentric devices could be used and, so far as the broad features of the invention are concerned, other apparatus for pressing the slide valve 100 against the block 25 might be used, for example one or more piston cylinder units might be employed. It will further be seen that the slide valve 100 reciprocates with a dwell at the end of each stroke and during these periods of dwell the

solenoid 165 is energized. The pistons 27 are reciprocated during the time that the slide valve 100 is stationary, but the amount of reciprocation and the time of reciprocation of the pistons 27 is adjustable. Thus the pistons 27 are moving only when the slide valve 100 is stationary but, in the case of most adjustments, they are not reciprocating during all of the time that the slide valve is stationary. Furthermore the slide valve 100 is moving only when the pistons are stationary and preferably the solenoid 165 is deenergized when the slide valve 100 is moving. The important point in this connection, however, is that the solenoid 165 or other means for exerting a strong force clamping the slide valve 100 shall be active when the pistons 27 are moving.

It will thus be seen that there has been provided by this invention apparatus in which the various objects hereinbefore set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. Apparatus of the class described comprising a block having a plurality of pump chambers, a plurality of pistons extending into said chambers, means intermittently reciprocating said pistons giving said pistons a dwell at the end of each stroke in each direction, discharge passages into which material is pumped, inlet passages from which material is drawn into said chambers, a slide valve having a plurality of each of two sets of ports, one set of ports being shaped to connect the discharge passages to the chambers and the other set being shaped to connect the inlet passages to the chambers, means intermittently reciprocating said slide valve giving said valve a dwell at the end of each stroke, an eccentric shaft in contact with said slide valve on the side thereof remote from said block, said eccentric shaft having eccentric cross-section opposite all of said discharge passages and opposite all of said inlet passages whereby when a rotative couple is exerted upon said eccentric shaft tending to turn it the slide valve is strongly urged against the block at all of the discharge and at all of the inlet passages, and means to exert such rotative couple tending to turn said eccentric shaft when the pistons are moving.

2. Apparatus of the class described comprising a block having a plurality of pump chambers, a plurality of pistons extending into said chambers, means intermittently reciprocating said pistons giving said pistons a dwell at the end of each stroke in each direction, discharge passages into which material is pumped, inlet passages from which material is drawn into said chambers, a slide valve having a plurality of each of two sets of ports, one set of ports being shaped to connect the discharge passages to the chambers and the other set being shaped to connect the inlet passages to the chambers, means intermittently reciprocating said slide valve giving said valve a dwell at the end of each stroke, a cam in contact with said slide valve on the side thereof remote from said block whereby when a rotative couple is exerted upon said cam tending to turn it the slide valve is strongly urged against the block to prevent leakage, and means to exert

such rotative couple tending to turn said cam when the pistons are moving.

3. Apparatus of the class described comprising a piston, a block having a chamber for the piston and having an inlet passage and having an outlet passage, a slide valve having a port shaped to connect the chamber with the inlet passage and having a port shaped to connect the chamber to the outlet passage, means to reciprocate the piston intermittently with a dwell at the end of each stroke, means to reciprocate the slide valve intermittently with a dwell at the end of each stroke, said last two means being timed to each other so that the slide valve is stationary when the piston is moving, means operating when the piston is moving to press said slide valve strongly against said block, said last named means also being associated with further means to press said slide valve against said block with a weaker force when said slide valve is moving.

4. Apparatus of the class described comprising a plurality of pistons, means for reciprocating the pistons intermittently with a dwell at the end of each stroke, a plurality of chambers in which the pistons reciprocate, a slide valve having a plurality of ports for admitting material to the chambers and a plurality of ports for discharging material from the chambers, a member having a surface against which the slide valve moves, said member having passages leading to the chambers, means for reciprocating the slide valve intermittently with a dwell at the end of each stroke, during one dwell all of the admitting ports being aligned with the passages and during the other dwell all of the discharging ports being aligned with the passages, the means for reciprocating the pistons and the means for reciprocating the slide valve being connected to a common source of power, and means for forcing the slide valve against the surface with a light force at all times and means for forcing the slide valve against the surface with a stronger force when the pistons are moving.

5. Apparatus of the class described comprising a plurality of pistons, adjustable means for reciprocating the pistons intermittently with a dwell at the end of each stroke said means being adjustable to vary the length of the strokes, a plurality of chambers in which the pistons reciprocate, a slide valve having a plurality of ports for admitting material to the chambers and a plurality of ports for discharging material from the chambers, a member having a surface against which the slide valve moves, said member having passages leading to the chambers, means for reciprocating the slide valve intermittently with a dwell at the end of each stroke, during one dwell all of the admitting ports being aligned with the passages and during the other dwell all of the discharging ports being aligned with the passages, the means for reciprocating the pistons and the means for reciprocating the slide valve being connected to a common source of power and so timed that when the pistons are moving the slide valve is stationary regardless of the setting of the adjustable means and when the slide valve is moving the pistons are stationary regardless of the setting of the adjustable means, and means for forcing the slide valve against the surface whenever the pistons are moving.

6. Apparatus of the class described comprising a plurality of pistons, adjustable means for reciprocating the pistons intermittently with a

dwell at the end of each stroke said means being adjustable to vary the length of the strokes, a plurality of chambers in which the pistons reciprocate, a slide valve having a plurality of ports for admitting material to the chambers and a plurality of ports for discharging material from the chambers, a member having a surface against which the slide valve moves, said member having passages leading to the chambers, means for reciprocating the slide valve intermittently with a dwell at the end of each stroke, during one dwell all of the admitting ports being aligned with the passages and during the other dwell all of the discharging ports being aligned with the passages, the means for reciprocating the pistons and the means for reciprocating the slide valve being connected to a common source of power and so timed that when the pistons are moving the slide valve is stationary regardless of the setting of the adjustable means and when the slide valve is moving the pistons are stationary regardless of the setting of the adjustable means, and means for forcing the slide valve against the surface with the light force at all times and means for forcing the slide valve against the surface with a stronger force when the pistons are moving.

7. In apparatus as claimed in claim 4, the combination with the parts and features therein specified, of a device under control of the operator for stopping the slide valve with the admitting ports aligned with the passages, whereby continued reciprocation of the pistons agitates material in the chambers and in the passages and in the admitting ports without pumping it.

8. In apparatus as claimed in claim 5, the combination with the parts and features therein specified, of a device under control of the operator for stopping the slide valve with the admitting ports aligned with the passages, whereby continued reciprocation of the pistons agitates material in the chambers and in the passages and in the admitting ports without pumping it.

9. In apparatus as claimed in claim 6, the combination with the parts and features therein

specified, of a device under control of the operator for stopping the slide valve with the admitting ports aligned with the passages, whereby continued reciprocation of the pistons agitates material in the chambers and in the passages and in the admitting ports without pumping it.

10. Apparatus of the class described comprising a plurality of pistons, means for reciprocating the pistons intermittently with a dwell at the end of each stroke, a plurality of chambers in which the pistons reciprocate, a slide valve having a plurality of ports for admitting material to the chambers and a plurality of ports for discharging material from the chambers, a member having a surface against which the slide valve moves, said member having passages leading to the chambers, means for reciprocating the slide valve intermittently with a dwell at the end of each stroke, during one dwell all of the admitting ports being aligned with the passages and during the other dwell all of the discharging ports being aligned with the passages, the means for reciprocating the pistons and the means for reciprocating the slide valve being connected to a common source of power, means for forcing the slide valve against the surface whenever the pistons are moving, and a device under control of the operator for stopping the slide valve with the admitting ports aligned with the passages, whereby continued reciprocation of the pistons agitates material in the chambers and in the passages and in the admitting ports without pumping it.
